UNITED STATES PATENT OFFICE.

CHARLES E. CANNADAY, OF WASHINGTON, DISTRICT OF COLUMBIA.

INSIDE-DOOR PROTECTOR AND GANG BOARD.

Application filed September 15, 1923. Serial No. 662,874.

This invention relates to inside door protectors and gang boards for freight cars and the like and has for an object to provide improved means for protecting the car door 5 against being bulged or broken open by the lading and to be permanently affixed in such position as to serve as a gang board when lowered to substantially horizontal position.

A further object of the invention is to 10 provide an inside door protector with improved means for holding it in protecting position, which means may be manually disengaged to lower the protector to gang board operating position.

15 A further object of the invention is to provide a gang board having improved means for co-action with an adjacent car to or from which lading is being transferred, adapted to be closed into the car to serve as a 20 protector for the door when occupying a substantially vertical plane.

With these and other objects in view, the invention comprises certain novel parts, elements, units, combinations, constructions 25 and interactions as disclosed in the drawings together with mechanical and functional equivalents thereof as will be hereinafter more fully described and claimed.

In the drawings:

30 Figure 1 is a view of the improved door protector and gang board, occupying a substantially vertical plane as seen from the inside of a car looking out through the open door.

35 Figure 2 is a section taken on line 2—2 of Figure 1.

Figure 3 is a vertical sectional view on line 3—3 of Figure 1.

40 Figure 4 is a plan view of two adjacent cars with the gang board occupying a position to facilitate the transfer of lading from one car to the other.

Figure 5 is a vertical sectional view showing the gang board co-acting with a plat- 45 form.

Like characters of reference indicate corresponding parts throughout the several views.

The improved door protector and gang 50 board, which forms the subject matter of this application, is adapted to be associated with freight cars of substantially the usual and ordinary type now in use embodying a floor 10 and door posts 11. It is to be understood, of course, that the present invention is capable of variations of size to corre-

spond to door openings of different dimensions and that the relative sizes of the device and car structure shown is not intended as any limitation upon the invention. 60

The protector comprises a plate 12, preferably of steel or other approved metal, although the present invention is in no way limited to the material from which the plate is constructed. 65

This plate 12 is permanently attached to the car by means of eye bolts 13 which are inserted through the floor of the car or some equivalent structure. The plate 12 is provided with perforations 14 operating in 70 conjunction with the eyes of the eye bolts to form hinges for the plate so that the said plate may occupy any position within the radius of movement possible by reason of the surrounding structure. 75

One of the positions of the plate 12 is a vertical position, as shown more particularly at Figures 1 and 3, in which position it serves to protect the door of the car which is not shown in the drawings, but 80 which it is understood is upon the exterior of the car, hung in any usual and ordinary manner. This vertical position is maintained by means of channel iron latches 15 which are pivoted at 16 to the door posts 85 11 so that these latches may swing from a vertical coincidence with the posts 11, in which position they are inoperative, down to embrace the top edge of the plate 12 as shown in Figures 1, 2 and 3, in which position they are operative, to maintain the plate 12 in its vertical position and, therefore, to act as a protector for the door to prevent the laden jamming against the door and doing damage thereto. 95

The plate 12 also serves as a gang board by being released from the latches 15 and lowered to a horizontal or approximately horizontal position. One of these positions is shown at Figure 4 wherein the gang 100 board is employed to form passage from the car upon which it is mounted to an adjacent car. This adjacent car is represented by the door posts 11' and floor 10'. It will be noted that the plate 12 is provided 105 with cut out notches 17 so that, in case the two cars are not "spotted" in exact register, the gang board may occupy the position shown at Figure 4 to form a passage from one car to the other for trucks and 110 the like as satisfactorily as though the cars were "spotted" exactly opposite each other.

As shown at Figure 5, the gang board comprising the plate 12 is shown bearing upon a fixed platform 18, its utility and use in such respects being that of the usual 5 and ordinary gang board.

From the foregoing description of the construction and assembling of the parts of the invention, it is believed that the use and operation will be clearly understood.

10 What I claim to be new is:

1. The combination with spaced door posts and a plate hinged to stand substantially vertically between the posts, said

15 plate having its upper corners cut out of a latching means for the plate comprising channels pivoted to the posts to swing to-

ward each other to span the cut out spaces and engage over and embrace the upper edge of the plate.

2. The combination with spaced posts 20 and a plate hinged to stand substantially vertically between the posts, said plate having the upper end corners cut out of a latching means for the plate comprising channels pivoted to the posts to stand vertically 25 in inoperative position and swing toward each other to span the cut out corners and engage over and embrace the upper edge of the plate.

In testimony whereof I affix my signature.

CHARLES E. CANNADAY.
